UNITED STATES PATENT OFFICE

136,213

DESIGN FOR A BOOKMARK OR SIMILAR ARTICLE

Hyman S. Aaronson, Meriden, Conn.

Application May 25, 1943, Serial No. 110,284

Term of patent 7 years

To all whom it may concern:

Be it known that I, Hyman S. Aaronson, a citizen of the United States of America, residing in Meriden, county of New Haven, and state of Connecticut, have invented a new, original, and ornamental Design for a Bookmark or Similar Article, of which the following is a specification, reference being had to the accompanying drawing, forming part thereof.

The figure on the drawing is a perspective view of a bookmark or similar article showing my new design.

I claim:

The ornamental design for a bookmark or similar article, substantially as shown.

HYMAN S. AARONSON.
